UNITED STATES PATENT OFFICE

2,584,820

DOUBLE-ACTING HYDRAULIC JACK

Raymond J. Steinhoff, Alhambra, Calif.

Application May 1, 1947, Serial No. 745,276

1 Claim. (Cl. 60—52)

1
This invention relates to an all-purpose double acting jack.

It is an object of the present invention to provide a jack motor of this type which has attaching portions thereon to which can be connected rods or other elements to be operated upon by the jack.

Other objects of the present invention are to provide a self-contained pump and jack construction wherein the jack itself will provide the reservoir for the oil to be pumped by the pump located on the side of the casing and wherein there is disposed within the casing telescoping parts adapted to be extended or retracted depending upon the direction to which a two way valve has been turned and wherein the oil will be completely contained within the casing of the jack.

Another object of the present invention is to provide within a hydraulic double acting jack an expandable reservoir for containing the oil to be extended between the parts to be extended and wherein within this reservoir is a piston backed up by a spring adapted to keep a pressure on the oil within this reservoir.

Other objects of the present invention are to provide a hydraulic double acting jack which is of simple construction, inexpensive to manufacture, easy to operate and efficient in operation.

For other objects and for a better understanding of the invention, reference may be had to the following detailed description taken in connection with the accompanying drawing, in which

Fig. 1 is an elevational view of a double acting jack with portions broken away and shown in section in order to show the internal parts of the jack motor and of the pump attached to the jack motor casing and extending laterally therefrom.

Fig. 2 is a transverse cross-sectional view taken on line 2—2 of Fig. 1.

Fig. 3 is a transverse cross-sectional view taken on line 3—3 of Fig. 1.

Fig. 4 is a cross-sectional view of the two way valve with the valve element turned to one position.

Fig. 5 is a cross-sectional view of the two way valve with the valve element turned to another position.

Fig. 6 is an elevation and fragmentary view of one of the one way ball valve fittings which are inserted through the casing from the exterior thereof.

Fig. 7 is a diagrammatic view of the system

2
with the two way valve turned to one position and with the pump operating to remove oil from the reservoir to the parts to be extended.

Referring now particularly to Fig. 1, 10 represents the movable cylinder of my double acting back motor on which there is a lug projection 11. To this lug projection 11 there is pivotally connected a pump handle 12 adapted to be worked up and down and to which there is connected a pump plunger 13 extending upwardly to a pump cylinder 14 projected downwardly from a laterally extending portion 15 which is in turn screw threaded to the cylinder 10 at one end thereon as indicated at 16. As the pump handle 12 is moved down, oil is drawn into the pump cylinder 14. As the pump handle is raised the oil will be forced outwardly of the same under pressure. The cylinder 10 serves as the principal motor chamber for oil. This chamber is indicated at 17 and oil is removed therefrom through a tube 18 entering the cylinder at 19 and connected with the other part of the cylinder 10 as indicated at 21. Oil entering at 21 is passed to the two way valve 22 which is adjustable by a handle portion 23 extending from the side of the cylinder. If the valve 22 is moved to one position as illustrated in Fig. 7, oil will pass through a passage 24 to a reservoir 25. Within this reservoir 25 is a piston 26 backed up by a conical spring 27 and adapted to maintain a pressure upon the oil within this reservoir 25 so that the fluid will be kept under pressure. The passage 24 is within a block or head 28 threaded into one end of the cylinder 10. The reservoir is provided by the fitting 29 screw threaded into the same end of the cylinder and against the threaded block 28. This fitting 29 has a threaded hole 31 serving as means by which the jack can be attached to a rod element to which work is to be imparted.

From the reservoir 25 oil passes through a passage 32, a one way check valve 33 and passage 34 to pump cylinder 14. On the upward movement of the plunger 13 of the pump, oil will be forced to a one way valve fitting 35, arcuate shaped passage 36, two way valve 22, passage 37 to central bore 38 of an inner piston member 39 screw threaded as indicated at 41 to the block 28. Oil will be delivered through the bore 38 to the opposite end of the piston 39 and will react against a block 42 screw threaded into an annular piston or ram 43 surrounding the piston 39. A piston packing cup 44 is fixed to the end of the piston 39. As pressure is built up in a motor chamber 45 in the end of the ram 43, the ram 43 will be

projected out of the movable cylinder 10. A packing cup 46 is disposed between the ram 43 and the interior of the movable cylinder 10. This packing cup is retained in place by locking plates 47 and 48. A packing gland 51 may be located in the locking plate 48. The plug 42 also has a threaded hole 52 by means of which the jack can be connected to a threaded rod. Port 60 serves as an air vent leading from the space between ram 43 and head 28 through cylinder 10 to the atmosphere.

The ball valve fittings are connected to the block 28 from the movable cylinder 10 and are constructed as shown more clearly in Fig. 6. The ball valve as shown in Fig. 6 includes an opening 15 or chamber 55 in which is disposed a ball 56 and a spring 57 for urging the ball against a seat 58. Oil, upon passing the ball, will enter the chamber 55 and pass outwardly through opening 59.

If the jack is to be retracted, the two way valve 22 is turned to the position shown in Fig. 5. The operation will then be reversed. Fluid will then flow from the motor chamber 45 toward the motor chamber 17. The oil under reversed operation will pass from the motor chamber 45 through the central bore 38 of the piston 39 and passage 31 to the valve 22 then through passage 24 to the reservoir 25. This is due to the fact that the oil passes through passage 32, from the reservoir 25 to the check valve 33 and passage 34 to pump cylinder 14. Operation of the plunger 13 will force the oil to valve fitting 35, passage 36 and two-way valve 22, through tube 18 to motor cylinder 17. Pressure in the motor cylinder 17 forces the head of the ram upwardly and retracts the block 42 fastened thereto. The pump 14 will be actuated and a pulling force will be placed upon the ends of the jack and will pull together any parts connected to the same. The reservoir 25 will receive the oil on its return passage and the piston and spring device therein will maintain the oil leaving the reservoir 25 under pressure.

While various changes shall be made in the detail construction, it shall be understood that such changes shall be within the spirit and scope of the present invention as defined by the appended claim.

I claim:

An all-purpose double acting jack comprising 50 a movable cylinder, a block fixed to one end of the movable cylinder, a piston anchored to the

block and extending into the movable cylinder, a ram surrounding the piston, said ram being spaced from the inner wall of the movable cylinder to provide a motor chamber within the movable cylinder, said ram being slideable out of the movable cylinder, a reservoir associated with the movable cylinder for at first receiving the oil leaving the motor chamber, spring pressure means within the reservoir placing the oil therein under pressure, a second motor chamber in said ram, a pump associated with the movable cylinder to draw oil from the reservoir and to force the same to the second motor chamber between the piston and the ram to extend the same relative to one another, and said ram being retracted by returning the oil to the motor chamber between the ram and the movable cylinder, and the block secured to the piston having passages for receiving oil from the reservoir for passage to the pump and for the return of the oil from the pump under pressure for delivery to the second motor chamber between the piston and ram, said piston having a central bore extending downwardly therethrough and said central bore being in communication with the passages within the block, said reservoir being disposed on the end of the movable cylinder adjacent to the block and comprising further a member screw threaded into the movable cylinder and said member having an attaching portion connecting the jack to a part to be worked by the jack and said ram having a member adapted for the attachment of the jack to a part to be operated by the jack, and a two-way valve connected with the block and the passages therein for reversing the flow of the oil.
